EXHAUST MUFFLING MEANS

Gail C. Starkweather and Lucien L. Haas, Youngstown, Ohio, assignors to Buffalo Pressed Steel Company, Inc., Buffalo, N. Y.

Application July 6, 1938, Serial No. 217,703

19 Claims. (Cl. 181—45)

This invention relates to improvements in mufflers or exhaust silencing means for internal combustion engines and the like.

One of the objects of this invention is to provide silencing means including a main passage and a by-pass or branch passage, and means for restricting the flow of gases through the main passage when the silencing means has a relatively low temperature, to render the same more effective when the engine is starting and when operating at low speeds. It is also an object of this invention to provide a muffler of this kind having a main passage and a branch passage, and in which the main passage is provided with a valve which may be actuated by means responsive to the temperature of the muffler for controlling the position of the valve. Another object is to provide a thermostatically controlled valve in the main passage which, when the muffler is cold, forces a greater part of the gases to flow through a branch passage and which is opened when the temperature of the muffler increases to permit gases to flow freely through both the main passage and the branch passage, to reduce the back pressure of the muffler. Another object is to provide a muffler with a valve in the main passage and thermo-responsive valve operating means which is exposed to the temperature of the gases flowing through the branch passage of the muffler. It is also an object of this invention to produce a muffler construction of this kind which is inexpensive and durable and which produces the maximum silencing effect when the engine is starting or operating at low speeds, and which will reduce the back pressure when the engine is operating at high speeds.

In the accompanying drawings:

Fig. 1 is a longitudinal, central, sectional view of a muffler embodying this invention.

Fig. 2 is a fragmentary longitudinal, central, sectional view of an end of the muffler, on a larger scale.

Fig. 3 is a fragmentary elevation, partly in section, of the muffler as seen from the other side, the outer shell of the muffler being in section to show the interior of the muffler.

Fig. 4 is a fragmentary longitudinal view of the muffler showing the conduit or inner shell and the thermostatic means for operating the valve arranged therein.

Fig. 5 is a transverse sectional elevation thereof, on line 5—5, Fig. 2.

Fig. 6 is a fragmentary, longitudinal sectional view of one end of a muffler provided with valve actuating means of modified construction.

Fig. 7 is a sectional elevation thereof showing the inner shell of the muffler in elevation and the outer shell in section.

Fig. 8 is another longitudinal view of one end of the inner shell of the muffler, the outer shell being omitted.

Our improvements may be applied to the exhaust system of an engine in any suitable or desired manner so as to provide a main passage which is constructed with the principal object of providing a passage of low resistance to the flow of gases, and in which the silencing of the exhaust is of secondary importance, and a second or branch passage which is designed mainly with the object of effectively silencing the exhaust, and in which the resistance of the flow of gases is of secondary importance. The flow of the exhaust through these two passages is controlled by thermostatically operated means responsive to the temperature of the silencing means in such manner that at relatively low temperatures, the exhaust will be passed mainly through the high resistance passage to produce good silencing, and at higher temperatures, which result from a greater demand of power from the engine, the exhaust will be passed mainly through the low resistance passage to reduce the back pressure in the exhaust manifold of the engine. Preferably, though not necessarily, the two passages are built into a single muffler which has a main passage for the gases and a by-pass or side passage which parallels the main passage for at least a portion of the length of the muffler. By way of illustration, we have shown our invention applied to a muffler of the straight-through type in which the exhaust gases may pass through a perforate conduit straight from the inlet of the muffler to the discharge thereof, but it will be obvious that this invention may also be applied to any other type of muffler.

The muffler shown has a housing including an outer shell A, one end of which is closed by means of an inlet head B having formed in one piece therewith an inlet duct b, to which the exhaust pipe of an engine may be connected. The other end of the outer shell is closed by means of a discharge head C having a similar discharge duct c, to which a tail pipe (not shown) may be connected. A housing of any other construction may be employed, if desired. The two ducts, in the construction shown, are also connected by means of an inner shell or conduit which forms the main passage of the muffler. This shell or conduit may be made of one or more tubular parts, that shown including a tubu-

40

45

50

55

lar part 10, one end of which is welded or otherwise secured within the inlet duct 5 of the muffler, and is provided with a suitable opening which may be in the form of apertures, or of any 5 suitable or desired form.

The inner conduit or shell shown also includes a tubular part 14, which in the construction shown is formed integral with a radial flange or annular partition 15 having an axially extending flange 16 which may be secured to or engage the outer shell A. The transverse part 15, consequently, forms a baffle or transverse wall extending from the inner shell or conduit to the outer one. The part 10 of the inner conduit 10 telescopes into the part 14 and may be secured thereto in any suitable manner, such for example 15 as by spot welding.

The inner shell or conduit shown also includes a tubular part 17, one end of which connects with 20 an end of the tubular part 14 and which is also provided with openings or a plurality of groups of perforations 18. These perforations may be similar to the perforations 11 and may be of the well known type formed by means of longitudinal slits in the inner shell, the metal at 25 one side of each slit being forced out of alignment with the metal at the other side of the slit so as to form a louver 18a extending over each opening, as shown in Fig. 5. Any other 30 perforations or openings may, however, be used. The part 17 of the inner shell or conduit extends to the discharge duct c of the muffler. The transverse wall or baffle 15 is provided with suitable 35 holes or openings 19. Since the perforations 11 are located in advance of the transverse baffle 15 and the openings 19 are in rear of the baffle, it will be obvious that gases may pass through 40 the muffler through the main passage provided by the inner shell or conduit and through the perforations 11 into a chamber 20 and then through the openings 19 in the transverse baffle 15 into the chamber 21, whereupon these gases 45 may again return to the main passage within the inner conduit through the openings or perforations 18. The muffler is, consequently, provided 50 with a side or branch passage which forms a by-pass around the main passage, and since the chambers 20 and 21 are of relatively large size to provide for expansion of the gases and also 55 for silencing of sound waves, it will be obvious that if the greater portion of gases were passed around the by-pass through the chambers 20 and 21, greater silencing effect would be produced, but this greater silencing effect would be accompanied by greater resistance to the flow of 60 the gases, and consequently, by greater back pressure in the exhaust pipe.

When an engine is operating at slow speeds and while being started, the amount of back 60 pressure built up by the exhaust is not great, for the reason that relatively small quantities of exhaust gases are passed through the muffler. If, however, an engine is operating at a high capacity, for example, when driving at high 65 speeds, greatly increased volumes of gas are forced through the muffler, and consequently, in mufflers as heretofore constructed, higher back pressure results. We have, consequently, devised means in the muffler for causing the gases to be 70 by-passed around the main passage when the engine is being started and operating at low speeds, and whereby the main passage will be wide open when the muffler becomes hot so that the gases discharged through the muffler will 75 encounter the minimum of resistance and will,

consequently, build up a low back pressure and these means include a valve arranged within the main passage between the openings or apertures 11 and 18 thereof. This valve is arranged, in the construction shown, in the tubular member 14 and is of the butterfly type, including a metal disk 24 suitably secured to a valve rod 25 pivoted in apertures in the tubular member 14. This valve rod is arranged to be swung about its axis to move the valve from a restricting 10 position shown in Figs. 1 and 2, to a wide open position in which the valve disk 24 lies in a plane approximately parallel with the axis of the inner shell or conduit, as shown in broken lines in Fig. 3. An end of the valve pin or rod 25 15 extending out of the inner shell part 14 is provided with suitable means for automatically swinging the valve into different positions, depending upon the temperature of the muffler. Any suitable means may be employed for this 20 purpose, and in the construction shown in Figs. 1 to 5, we have provided a bi-metallic thermostatic element 27 for this purpose, which is rigidly supported on a part of the muffler at one 25 end thereof, for example, by means of a bracket 28 secured to the part 17 of the inner shell. The part of the valve stem 25 which extends out of the inner shell is provided with a suitable crank arm 29 having a crank pin 30 which extends into a bent over or hook portion 31 of 30 the end of the thermostatic element 27. Any other means for connecting the thermostatic element 27 with the stem 25 of the valve for turning the same may be provided.

The thermostatic element is so constructed 35 that when cold, it will occupy a position such, for example, as that shown in Figs. 1 and 2, in which the valve 24 will extend transversely of the inner shell or conduit in such a manner as to obstruct or restrict the flow of gases through 40 the inner conduit. Preferably the valve does not fit tightly within the conduit so that when the valve is in its flow restricting position, some of the gases may flow through the main passage within the inner conduit, but the greater portion 45 of the gases will be forced to by-pass the inner conduit. As the thermostatic element becomes heated, it will move the valve 24 toward its open position, in which it extends substantially parallel to the axis of the inner shell, 50 as shown in broken lines in Figs. 3 and 4. In order to prevent the thermostatic element, after 55 it becomes excessively hot, from moving the valve beyond the wide open position, a stop pin 32 may be provided which is secured to the part 14 of the inner shell and extends outwardly into position to engage the crank arm 29 and prevent further swinging of the same, as shown in Fig. 3.

It will be obvious from the foregoing construction that when the muffler is cold, the valve 60 will be in the flow restricting position in the main passage, so that when the engine is being started, the muffler will produce the maximum silencing 65 effect by forcing the greater part of the gases to by-pass the main passage through the silencing chambers 20 and 21. When the engine is running at moderate speeds such, for example, as in city driving, the thermostat will become only slightly heated and will continue to force the greater part of the gases to by-pass the main passage. 70 When, however, the car is driven at higher speeds, the muffler will become heated to a higher temperature so that the thermostatic element 27 will move the valve into its wide open position, so that the back pressure of the muffler is reduced 75

to a minimum and so that the engine may develop its maximum power.

The balance of the muffler may be of any suitable construction to provide additional silencing properties. By way of example, we have herein shown another transverse partition or baffle 35 extending from the inner to the outer shell and having apertures 36 through which sound waves may pass into a chamber 37 for silencing the noise of the exhaust. If desired, an intermediate shell 39 may be provided about perforate portions of the inner shell. This intermediate shell may, for example, be made in two or more parts having their adjacent longitudinal edges secured together so as to form between the inner and intermediate shells chambers 40 and 41 for silencing high frequency sound waves. It will be noted that these silencing means operate on the exhaust, regardless of whether the same passes through either or both of the passages of the muffler, but the action of these silencing means is more effective when the valve 24 is closed or nearly closed, since in that case, the flow of gas past these silencing means will be steadier or more uniform and the sound partly cancelled before it is exposed to the action of these means. Furthermore, it will be noted that the valve 24 when in closed or flow restricting position still permits some gas to flow past the valve and straight through the conduit or inner shell. The gas pulses and sound waves passing the valve at such times, when reunited with the part of the gas pulses and sound waves which have passed through the branch passage, will be out of phase therewith, thus resulting in a further cancellation of sound waves. By permitting some gas to pass the valve even when the same is in closed position, a reduction of back pressure results. Any other silencing devices may be provided, if desired.

In Figs. 6 to 8 inclusive, we have illustrated a modified form of the thermostatic device for controlling the flow of gases through the main passage of the muffler, and this device has been shown as incorporated in the same type of muffler as illustrated in connection with Figs. 1 to 5. In this construction, the valve 45 has a stem 46 which is provided on its outer end with a crank arm 47 having a pin 48 which engages in a slot formed in a hook member or bracket 50. The hook member or bracket is secured to one end of the tubular member 51 provided with a plurality of corrugations 52 and secured at its other end to the inner shell part 53, for example, by means of spot welds as shown at 54. As this corrugated member becomes heated, it expands, and upon cooling, contracts to its initial length. Consequently, when the corrugated member is cold, the parts will occupy the positions shown in Fig. 6, in which the valve 45 is in the flow restricting position transversely of the main passage of the muffler. As the corrugated tubular member becomes heated, it moves the valve toward open position, and in Figs. 7 and 8, the valve is shown in the full open position. Movement of the valve beyond its wide open position may be stopped in any suitable manner, for example, by forming a shoulder 55 on the hook member or bracket 50 which is so located that when the valve is in wide open position, as shown in Fig. 7, the shoulder 55 engages the valve stem 46 to prevent further movement of the member or bracket 50. In operation, the corrugated thermostatic sleeve shown in Figs. 6 to 8 is similar to the bi-metallic thermostat 27 disclosed in Figs. 1 to 5. In both constructions, the thermostatic element may, of

course, be selected to operate as desired. It may, for example, be desirable to select a thermostatic element which will retain the valve in its flow restricting position until the muffler becomes quite hot, so that the maximum silencing effect of the muffler will be effective during ordinary driving and until the car is driven at high speeds. If desired, the thermostat may be selected so that a gradual opening of the valve will take place. Consequently, when operating at moderate speeds, the exhaust of the vehicle will be only partly silenced.

While the thermostatic device may be secured in any suitable or desired part of the muffler, it will be noted that in the construction shown, the thermostatic devices are connected in heat conducting relation to the inner shell or conduit and are also located in a path of gases flowing through the by-pass about the main passage so that the thermostatic device will be subject to the temperatures within the muffler, regardless of whether the gases flow through the main passage or through the by-pass.

By means of this invention, it will be evident that a muffler constructed in accordance therewith will act to afford the maximum silencing of the exhaust under conditions existing when very little back pressure develops, owing to the small volume of gas flowing through the muffler. When, however, more power is demanded of the engine, the greater volume of gas discharged through the muffler rapidly heats the thermostatic element so that the valve is opened to permit gas to pass substantially without obstruction through the main passage, as well as through the parallel or side passage, so that the back pressure will be reduced to a minimum. The fact that there is less silencing at higher speeds than at low speeds or idling is not objectionable, since the noise of the exhaust is less noticeable at higher speeds because of other noises which occur at high speeds. By the use of the invention herein described, it is also possible to construct mufflers capable of producing very superior silencing effects at low or moderate speeds, at which the resistance to the limited flow of gases is of no importance, without having these superior silencing effects handicap the engine when operating at higher speeds.

We claim as our invention:

1. Means for muffling the exhaust of an internal combustion engine, including means forming a main gas passage of relatively low resistance to the flow of exhaust gases, valve means arranged in said duct, means forming a second gas passage of higher resistance to the flow of said gases than said main passage and having greater silencing effect upon the exhaust and connecting with said main passage in advance of said valve, and means responsive to the temperature of gases passing through said muffling means for urging said valve into a position to obstruct the passage of gases through said main passage when said muffling means are relatively cool and into an open position when said muffling means are hot.

2. Means for muffling the exhaust of an internal combustion engine, including means forming a main gas passage, means forming a branch passage of higher resistance to flow and greater silencing effect upon the exhaust than said main passage, said branch passage being connected at its inlet and discharge ends with said main passage, valve means arranged in said main passage intermediate of the portions connecting

with said branch passage, and means responsive to the temperature of said muffling means and connected with said valve means for moving said valve means into flow obstructing position when 5 said muffling means is relatively cool to force gases to pass through said branch passage and to open said valve means when said muffling means becomes hot.

3. A muffler having shells arranged therein to 10 provide a main passage for gases and a branch passage, a valve in said main passage, said valve occupying a position, when said muffler is cold to restrict the flow of gases through said main passage and cause gases to flow through said 15 branch passage, and means responsive to changes of temperature of said muffler for moving said valve toward open position when the temperature of said muffler rises, to open said main passage.

20 4. A muffler having shells arranged therein to provide a main passage for gases and a branch passage terminating in said main passage, a valve in said main passage intermediate of the portions thereof in which said branch passage 25 terminates and which when in closed position, restricts the flow of gases in said main passage, thereby increasing the flow of gases through said branch passage, and means responsive to changes in temperature of said muffler to open said valve 30 when the muffler is hot to facilitate the flow of gases through said main passage.

5. A muffler having a shell providing a main passage for gases and having an opening through 35 which gases may pass, a second shell arranged to receive gases discharged through said opening in said first shell and forming a branch passage for gases, and a valve in said first shell arranged in rear of said opening and which may be moved into a position to restrict the flow of 40 gases through said first shell and into an open position to permit gases to flow freely through said first shell, and means responsive to changes in temperature within the muffler for moving said valve into open position when the temperature 45 in the muffler is high and into flow restricting position when the temperature in the muffler is low.

6. A muffler having a pair of nested shells spaced apart to form a passage for gases between 50 said shells, and a passage within the inner shell, the inner of said shells having an opening through which gases may pass from one passage to another, a valve in said inner shell which, when in open position, permits substantially unobstructed flow of gases through said inner shell and which may be moved into position to restrict the flow of gases through said shell, and temperature responsive means in said muffler for moving said valve into restricting position when 55 said muffler is relatively cool and into a less restricting position when said muffler becomes warmer.

7. A muffler having a perforate inner shell 60 forming a main passage for gases, a shell arranged about and spaced from said inner shell and forming therewith a branch passage for gases, a valve in said inner shell with perforations located in front of and in rear of said valve through which gases may pass from said inner shell into said branch passage and from said branch passage back to said inner shell, and 65 thermostatic means arranged within said muffler for moving said valve into position to restrict the flow of gases to said main passage when the 70

muffler is cold and for moving said valve into open position when the muffler becomes heated.

8. A muffler including an inner shell providing a main passage for gases, a shell arranged about and spaced from said inner shell and forming therewith a by-pass for gases, a valve in 5 said inner shell for controlling the flow of gases through said inner shell and through said by-pass, said inner shell having openings arranged in advance and in rear of said valve through which gases may flow into and out of said by-pass, a stem for said valve which extends out of said inner shell, and a thermostatic device arranged in said by-pass and secured to said inner shell and cooperating with said valve stem for moving 10 said valve into open position when the muffler is hot and into flow resisting position when the muffler is cold.

9. A muffler including an inner shell providing a main passage for gases, a shell arranged about 20 and spaced from said inner shell and forming therewith a by-pass for gases, a valve in said inner shell for controlling the flow of gases through said inner shell and through said by-pass, said inner shell having openings arranged 25 in advance and in rear of said valve through which gases may flow into and out of said by-pass, a stem for said valve which extends out of said inner shell, a bi-metallic thermostat arranged in said by-pass and having one end there- 30 of secured to said inner shell and having the other end thereof connected with said valve stem for moving said valve into open position when the muffler is hot and into flow resisting position when the muffler is cold.

10. A muffler including an inner shell providing a main passage for gases, a shell arranged about and spaced from said inner shell and forming therewith a by-pass for gases, a valve in 40 said inner shell for controlling the flow of gases through said inner shell and through said by-pass, said inner shell having openings arranged in advance and in rear of said valve through which gases may flow into and out of said by-pass, a tubular member provided with substan- 45 tially annular corrugations and having one end thereof secured to said inner shell and the other end thereof connected with said valve for moving said valve into open position when the muffler is hot and into flow restricting position when 50 the muffler is cold.

11. A muffler including an inner shell providing a main passage for gases, a shell arranged about and spaced from said inner shell and forming therewith a by-pass for gases, a valve in said 55 inner shell for controlling the flow of gases through said inner shell and through said by-pass, said inner shell having openings arranged in advance and in rear of said valve through which gases may flow into and out of said by-pass, a stem for said valve which extends out of said inner shell, a tubular member arranged in said by-pass and having substantially annular corrugations and having one end thereof secured to said inner shell and the other end thereof 60 secured to said valve stem for moving said valve stem into flow restricting position when the muffler is cold and into open position when the muffler is hot.

12. A muffler including an inner shell forming a main passage for gases, a shell arranged about and spaced from said inner shell, and forming therewith a by-pass for gases about said main passage, said main passage having openings 70 communicating with said by-pass, a valve 75

- in said inner shell arranged with openings spaced in front of and in rear of said valve, a stem rotatable about its axis to move said valve into different relations to said inner shell and having a crank portion, a thermostat arranged in said muffler and engaging said crank portion of said valve for moving said valve into open position when the muffler is hot and into flow restricting position when the muffler is cool.
- 5 13. A muffler having an inner shell forming a passage for gases and provided with perforations arranged lengthwise thereof, sound deadening chambers arranged in said muffler about said passage and communicating with each other and with said perforations to provide about said passage a by-pass including said sound deadening chambers, and a valve in said inner shell and movable into a position to vary the flow of gas through said passage and said by-pass.
- 10 14. A muffler having an inner shell forming a passage for gases and provided with perforations arranged lengthwise thereof, sound deadening chambers arranged in said muffler about said passage and communicating with each other and with said perforations to provide about said passage a by-pass including said sound deadening chambers, a valve in said inner shell and movable into a position to vary the flow of gas through said passage and said by-pass, and thermostatic means for controlling the position of said valve to open the same when the muffler is hot and to move the same into flow restricting position when the muffler is cool.
- 15 15. A muffler including an inner shell forming a main passage for gases, a shell arranged about and spaced from said inner shell and forming therewith a branch passage for gases about a portion of said inner shell, heat responsive means arranged in said branch passage, and flow controlling means in said inner shell which are actuated by said heat responsive means to restrict the flow of gases in said main passage when the muffler is relatively cool and to permit free flow of gases through said main passage when said muffler is hot.
- 20 16. A muffler including an inner shell forming a main passage for gases, a shell arranged about and spaced from said inner shell and forming therewith a branch passage for gases about a portion of said inner shell, heat responsive means arranged in said branch passage and secured on said inner shell, and flow controlling means in said inner shell which are actuated by said heat responsive means to restrict the flow of gases in said main passage when the muffler is relatively cool and to permit free flow of gases through said main passage when said muffler is hot.
- 25 17. Means for muffling the exhaust of an internal combustion engine, including means forming a main gas passage of relatively low resistance to the flow of exhaust gases, valve means arranged in said duct, means forming a second gas passage of higher resistance to the flow of said gases than said main passage and having greater silencing effect upon the exhaust and connecting with said main passage in advance of said valve, means responsive to the temperature of gases passing through said muffling means for urging said valve into a position to obstruct the passage of gases through said main passage when said muffling means are relatively cool and into an open position when said muffling means are hot, and sound silencing means common to both of said passages.
- 30 18. Means for muffling the exhaust of an internal combustion engine, including means forming a main gas passage, means forming a branch passage of higher resistance to flow and greater silencing effect upon the exhaust than said main passage, said branch passage being connected at its inlet and discharge ends with said main passage, valve means arranged in said main passage intermediate of the portions connecting with said branch passage, means responsive to the temperature of said muffling means and connected with said valve means for moving said valve means into flow obstructing position when said muffling means is relatively cool to force gases to pass through said branch passage and to open said valve means when said muffling means becomes hot, and sound silencing means operatively associated with said main passage and located rearwardly of said branch passage and which acts on all gases passing through either of said passages.
- 35 19. Means for muffling the exhaust of an internal combustion engine, including means forming a main gas passage, means forming a branch passage of higher resistance to flow and greater silencing effect upon the exhaust than said main passage, said branch passage being connected at its inlet and discharge ends with said main passage, valve means arranged in said main passage intermediate of the portions connecting with said branch passage, means responsive to the temperature of said muffling means and connected with said valve means for moving said valve means into flow obstructing position when said muffling means is relatively cool to force gases to pass through said branch passage and to open said valve means when said muffling means becomes hot, said valve when in position to produce the maximum obstruction to the flow of gases, providing a passage for a small part of the exhaust through the main passage for mixture with the part of the exhaust which has passed through said branch passage.
